Primary Examiner — Paula Allen Greene(74) *Attorney, Agent, or Firm* — Jon Gibbons; Fleit Intellectual Property Law(57) **CLAIM**

The ornamental design for the frame as shown and described.

DESCRIPTION

FIG. 1 is a perspective view of a frame showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the frame thereof.

The broken lines in FIGS. 1, 2, and 3 illustrate portions of the frame that form no part thereof. The broken lines in FIG. 8 illustrate the environment in which the design resides; the broken lines form no part of the claimed design.
